Attorneys.

UNITED STATES PATENT OFFICE.

THOMAS ALEXANDER BOYD AND HAROLD ARTHUR BOYD, OF GLASGOW, SCOTLAND.

TWISTING AND DOUBLING MACHINE.

1,384,041.

Specification of Letters Patent. Patented July 12, 1921.

Application filed December 11, 1919. Serial No. 344,264.

(GRANTED UNDER THE PROVISIONS OF THE ACT OF MARCH 3, 1921, 41 STAT. L., 1313.)

To all whom it may concern:

Be it known that we, THOMAS ALEXANDER BOYD and HAROLD ARTHUR BOYD, subjects of the King of the United Kingdom of Great Britain and Ireland, and residing at Glasgow, Scotland, have invented a certain new and useful Improvement in Twisting and Doubling Machines for which we have filed 5 applications in Great Britain, March 16, 1917, Patent No. 113,687, and in France March 16, 1918, Patent No. 489,305, of which the following is a specification.

This invention relates to detector mechanism for twisting and doubling machines 15 in which a rod normally urged upward and carrying the upper delivery roller is normally detained against upward movement by a catch plate but is freed from the catch plate and permitted to ascend by the action 20 of a cam on the detector in the event of breakage of the yarn.

According to the invention the detectors 25 are fitted in a detector box forming an intermediate member pivoted to the catch plate and adapted to act on the rod to disengage it from the catch plate on the fall of a detector into the path of the cam.

The invention also includes improved 30 forms of detector through which comes the yarn from the creel, such detectors being checked for engagement by a projection on the spring-pressed hinged cover of the detector box serving to maintain the detectors in working position.

35 The invention further includes a detector arranged to operate on failure of the twisted yarn between the delivery roller and the twisting bobbin, such detector being removable and replaceable while the machine 40 is working.

Figure 1 shows in side elevation the detector mechanism.

Figs. 2 and 3 show respectively in side elevation and in front elevation to enlarged 45 scale the detector box.

Figs. 4 and 5 show, respectively, in side elevation and in front elevation a flat detector.

Figs. 6 and 7 show respectively in side elevation and in front elevation a curl detector.

Fig. 8 shows in end elevation the cover of the detector box.

1 denotes a driving cylinder, 2 a band to drive the spindle 3, 4 a band-tightening pul-

ley, 5 a weighted lever carrying the pulley 55 4, 6 an upright rod with catch 6¹, the rod being normally held in raised position by the weighted lever 5, 7¹ a catch plate, 7 the stop lever, 8 the top rail, 9 a cam shaft and 10 and 11 upper and under delivery rollers. 60 These elements are all of known construction, being disclosed for example in the specification of British Patent No. 18920 of 1888. Instead of being mounted on the rod 6, as heretofore, the detectors 12 are carried 65 in the upper end of the detector box 13, which is pivoted on the rearward end 13⁴ of the catch plate 7¹ and extends upward in front of the cam shaft 9. The detector box 13 has vertical slits 13¹ which carry the detectors 12 and hold them when sustained by the yarn over the cam shaft 9. On the rear side of the detector box 13, i. e., on the side nearest the cam shaft, is hinged a spring 70 cover 13² to admit the detectors and maintain them in working position. As will be evident, when a yarn fails and its detector falls into the path of the cam, the detector box 13 is pressed forward away from the cam shaft. Adjustably mounted in the detector box 13 at a point between the detectors 12 and the pivot 13⁴ is a screw 13³ 75 disposed transversely of the cam shaft 9. The horizontal limb of the rod 6 is cut off at a point just clear of the detector box 13 80 and the end 6³ of the said limb is formed with a chin to receive pressure from the screw 13³ when the cam acts on a detector 12. The chin on the end 6³, on rising with 85 the rod 6, allows the point of the screw 13³ to pass below it. Pressure of the screw on the chin on failure of yarn and fall of a detector forces the rod 6 outward to bring the catch 6¹ clear of the catch plate 7¹, 90 whereupon the rod 6 rises with the following results:—lowering the lever 5 and slackening the band 2, gripping the band 2, raising the top delivery roller 10, and permitting the detector box 13 and detectors 12 95 to fall away from and be clear of the cam. 100 When the rod 6 is then depressed until the catch 6¹ engages with the catch plate 7¹, the entire mechanism is again restored to working position, i. e., the spindle band 2 is released and is tightened, the roller 10 is lowered on to the roller 11, and the detectors 12 105 are brought into operative relation with the cam shaft 9.

The detectors for the yarn coming from the creel may each be formed as shown at 14 in Figs. 4 and 5 of a piece of flat steel with an eye 14¹ at the upper end to receive 5 the yarn at the upper end. Each such detector 14 passes downward through the slit in the detector box so that, when a yarn has failed, its lowest point comes into the path of the cam shaft. On the edge of the detector 10 at the open side of the slit a check 14² is formed at a point between the eye 14¹ and the lower end. On the spring-pressed cover 13² of the detector box 13 is formed a projection 13³, which, when the cover 13² is 15 closed, enters the checks 14² and holds the detectors in position. The detectors may also each be formed from a round rod having a curl at its upper end and flattened as shown at 15 in Figs. 6 and 7 and checked at 20 15². In a slit in the detector box 13 is mounted a detector 16 formed of a piece of wire comprising a U-shaped loop having a limb 16¹ which slides in a slot in the detector box 13 and a limb 16² bent outward away 25 from the slot in the detector box 13 and away from the cam shaft 9 and then bent and carried downward until it rests upon and is sustained clear of the cam shaft by one end 7⁴ of the lever 7. The lever 7 is pivoted at 7² to the catch plate 7¹. One end of 30 the lever 7 forms a guide 7³ for the twisted yarn 17 coming from the delivery rollers 10 and 11. The other end 7⁴ of the lever 7 projects below the cam shaft 9 where it is counterbalanced. The tension of the twisted 35 thread 17 keeps the end 7³ in a downward position and the end 7⁴ in an upward position. It will thus be understood that the lever 7, when depressed by the tension of the 40 twisted yarn 17, will sustain the detector 16 above described, and, when the twisted yarn 17 fails, the detector 16 will descend into the path of the cam 9 and operate the stop-motion mechanism.

45 What we claim is:—

1. In a detector mechanism for twisting and doubling machines, in combination, a

rod, an upper delivery roller carried by said rod, a catch plate normally detaining said rod against movement, a cam, a detector box pivoted to said catch plate, detectors in said box, said detectors normally sustained by the yarn but adapted on failure of the yarn to fall into the path of the cam, and means on said detector box engageable with said rod to disengage said rod from the catch plate on the fall of a detector into the path of the cam.

2. In a detector mechanism for twisting and doubling machines, in combination, a detector box formed with slits, a spring-pressed cover hinged to said box, said cover having a projection, and detectors accommodated in said slits and each checked along one edge for engagement by said projection.

3. In a detector mechanism for twisting and doubling machines, in combination, a lever one end of which serves as a yarn guide, a rod, an upper delivery roller carried by said rod, a catch plate normally detaining said rod against movement, a cam, a detector box pivoted to said catch plate, said box formed with a slot, detectors in said box, one of said detectors being removably fitted in said slot and normally sustained by the opposite end of said lever clear of said cam, but movable into the path of said cam when said lever is tilted on failure of the yarn, the remaining detectors being normally sustained by the yarn, but adapted on failure of the yarn to fall into the path of said cam, and means on said detector box engageable with said rod to disengage said rod from said catch plate on movement of a detector into the path of said cam.

In testimony whereof we have signed our names to this specification in the presence of two subscribing witnesses.

THOMAS ALEXANDER BOYD.
HAROLD ARTHUR BOYD.
